UNITED STATES PATENT OFFICE.

HORACE LEOPOLD TUCKER BUCKLE, OF YIEWSLEY, ENGLAND, ASSIGNOR TO VICTOR TALKING MACHINE COMPANY, A CORPORATION OF NEW JERSEY.

SOUND-REPRODUCING MACHINE.

Application filed November 5, 1924, Serial No. 747,892, and in Great Britain February 5, 1924.

My invention relates to sound reproducing machines or talking machines, and particularly to those machines wherein the angular velocity of the turntable and the record rotated thereby may be constantly and regularly increased or diminished during the travel of the reproducer over a disc record during the reproduction of sound. This type of talking machine has certain advantages over those machines wherein the angular velocity of the turntable and record is maintained constant during the reproduction of sound from a disc record particularly in the length of a selection which may be recorded in the record tablet. In those machines wherein the angular speed of the turntable is so varied, a much longer selection can be recorded on the tablet than can be when it is rotated at a constant angular velocity.

My invention relates then to the recording or reproducing of sound on and from a record tablet in which the angular speed of the rotation of the tablet or record is constantly increased, if the recorder or reproducer moves inwardly from the periphery toward the center of the tablet in recording or reproducing sound, or is constantly decreased, if the recorder or reproducer moves outwardly from the center toward the periphery of the tablet or record in recording or reproducing sound.

One of the objects of the present invention is to provide, in a mechanism of the type above specified, improved means for accurately increasing or reducing the angular velocity of the turntable by varying the position of the governor friction pad by and from the tone arm without substantially limiting or restricting the free swinging movement of the tone arm.

A further object of my invention is to provide improved means for substantially converting a machine which will operate to rotate a record at a variable angular velocity and hereinafter termed for brevity a "variable speed" machine, into a machine which will rotate the record at a constant angular velocity and hereinafter termed for brevity a "constant speed" machine, and conversely, from a "constant speed" machine into a "variable speed" machine.

A further object of my invention is to produce a talking machine which may be converted into a "constant speed" machine or

a "variable speed" machine at will by merely effecting a simple adjustment, preferably accomplished by throwing a lever into one position for "constant speed" record reproduction and into another position for "variable speed" record reproduction.

A further object of my invention is to provide a machine of the interchangeable or convertible type above referred to with a speed adjusting mechanism which may be operated to increase or diminish the speed of the rotation of the turn-table whether the machine be operating as a "constant speed" machine or as a "variable speed" machine.

It has heretofore been proposed to rotate the turn-table slowly during the recording and reproducing of sound, when the needle or stylus is at the periphery of the record tablet and at a gradually increasing angular speed as the stylus moves toward the center of the record so that the linear speed of that portion of the sound record groove, which is in engagement with the stylus at any time, will be constant (constant needle speed). To give a constant needle speed to the record, the angular speed of rotation of the turntable must vary inversely with the distance of the stylus from the center of the record. But in such constant needle speed mechanisms, with a 12 inch record disc, wherein the sound groove begins near the periphery of the disc, and ends for instance 2 inches from the center of the disc, the angular speed of the record at the end of the reproduction must be substantially three times greater than it is at the commencement. In such constant needle speed machines, therefore, wherein the variation of the turntable speed is produced by varying the speed of the motor, the governor must be capable of giving an acceleration of from

lowest operative speed to highest operative speed of at least one to three. It is difficult to construct a governor which will regulate properly over so wide a range of speed, but it is essential that the governor shall control the speed of the motor at all times with absolute accuracy, because otherwise the reproduction will not be in tune.

Moreover, in constant needle speed recording and reproduction, the drag of the reproducing stylus at the periphery of a 12 inch disc will also be substantially three times as great as it is two inches from the center of the record. This drag is over-

- come to a great extent in reproducing sound at a constant angular speed, because of the high linear speed of the groove under the stylus and the momentum of the turntable.
- 5 But in constant needle speed talking machines, the angular speed of the turntable is slow when the stylus is at the periphery of the record and the drag on the motor at this time is difficult to control by the governor and tends to make the reproduction of sound out of tune.
- 10 The object of my invention is to obtain a record and a machine with which it may be played wherein a considerably longer selection may be recorded and reproduced on a record of given diameter than can be reproduced at a constant angular speed, and which will be free from the difficulties above noted.
- 15 20 A further object of my invention is to accelerate the angular speed of the turntable at a considerably lower rate than that necessary to produce constant needle speed.
- 25 A further object of my invention is to rotate a record on a variable speed machine during the reproduction of sound from the peripheral convolution of the groove considerably faster than it would be rotated in reproducing sound from the peripheral grooves of a constant-needle-speed record, but considerably slower than it would be rotated in reproducing sound from the corresponding peripheral grooves of a constant angular speed record. This operation also has the advantage that the drag of the needle at the peripheral portion of a record is satisfactorily overcome by the momentum of the turntable, while the acceleration of the motor from the slow
- 30 35 40 45 to the high speed, may be made to be comparatively small, and well within the certain and accurate control of a well designed and constructed flyball governor mechanism.
- 50 45 Further objects of my invention will appear in the specification and claims below.

In the drawings forming a part of this specification and in which the same reference characters are employed throughout the various views to designate the same parts,

55 Fig. 1 is a plan view of a portion of a talking machine embodying my invention with tone arm and turntable omitted for the sake of clearness but with the positions of the same indicated in dot and dash lines. In this view the mechanism is set to operate as a "variable speed" machine and the parts are in the relative positions in which they are when the reproducing stylus is in the outermost or largest convolution of a sound record groove.

60 65 Fig. 2 is a plan view similar to Fig. 1 but with the parts in the positions in which they are when the reproducing stylus is in

that convolution of the sound record groove of smallest diameter; that is to say, nearest the center of the record.

Fig. 3 is a plan view of the mechanism shown in Figs. 1 and 2 but with the mechanism set to operate as a "constant speed" machine, of the type used to reproduce ordinary records.

Fig. 4 is a side elevational view of a portion of a turntable, the tone arm, the goose-neck and the reproducer. In this figure also is illustrated a portion of the mechanism comprising my invention and more particularly the manner in which the mechanism is attached to and actuated by the tone arm. The pivotal mounting of the variable speed cam lever or member is here shown in vertical cross-section.

Fig. 5 is a plan view and Fig. 6 is a side elevational view of the friction pad carrying member.

Figs. 7 and 8 are respectively plan and side elevational views of the friction pad controlling member.

Figs. 9 and 10 are respectively plan and side elevational views of the main conversion motion member.

Fig. 11 is a vertical sectional view on the line 11-11 of Fig. 1.

Fig. 12 is a vertical sectional view on the line 12-12 of Fig. 2.

Fig. 13 is a vertical sectional view on the line 13-13 of Fig. 3.

The talking machine to which my invention may be applied or adapted may comprise the motor-board 1 to the under side of which is secured the motor frame 2 in which is journaled the spring barrel 3 provided with the usual driving gear 4 driven by said spring barrel 3 and meshing with and driving a worm 5, fast on the turntable spindle 6. The said spindle 6 may be provided with a worm gear 7 meshing with and driving a worm 8 on the governor shaft 9 which is journaled in bearings 10 on the motor frame 2.

Above the motor-board 1 are the turntable 11 mounted on and rotated by and with the spindle 6, and the tone arm 12, the outer end of which may be provided with a gooseneck 13 to which may be attached a sound box or reproducer 14 adapted to hold a stylus 15 in position to cooperate with the record groove in a disc record 16 placed on the turntable 11. While other flyball governor mechanisms may be used in carrying out my invention, I prefer to employ a construction which I have found to be very sensitive and accurate when operated over great ranges of speed and which is disclosed in Letters Patent of the United States, No. 1,520,008, granted December 23, 1924.

Such a flyball governor mechanism comprises the governor shaft 9 upon which is mounted a governor disc 17 relatively free

to slide on the governor shaft 9 longitudinally thereof, and preferably provided with a hub or collar 18 integral therewith. Also mounted upon the shaft 9 and rigidly secured thereto is a fixed collar 19. Between and connecting the fixed collar 19 with the slidable friction disc 17 are a plurality of connecting members each comprising a relatively long leaf spring 20 and a relatively short rigid arm 21, said arms being pivotally connected at one end to the fixed collar 19 and being rigidly secured at the other end to a weight or flyball 22 by a screw 23, said screws 23 serving to secure the springs 20 and the rigid members 21 firmly together and to the weights or flyballs 22.

Between the fixed collar 19 and the hub 18 of the governor disc 17 and tending to hold them apart is a spiral compression spring 24 which surrounds the governor spindle 9.

In this governor mechanism in order to prevent the pull of the weights 22 on the governor disc 17 from becoming excessive, the weights 22 are mounted on the connecting members between the fixed collar 19 and the governor disc 17 substantially nearer to the fixed collar than to the governor disc, the distance of the weights from the fixed collar being, for example, from one-half to one-third of the distance of the weights from the governor disc.

The pull of the weights increases rapidly with the distance that they move away from the axis of the rotation of the shaft and therefore it is desirable that the weights should not move too far away from the axis of the shaft and consequently they should be connected to the spindle by the relatively short rigid arms 21.

Cooperating with the friction disc 17 is a friction pad 25 mounted on and carried by the friction pad carrying member 26. As the governor rotates the weights 22 fly outwardly tending to straighten the slightly curved springs 20 and to pull the governor disc 17 toward the left (in Fig. 1) and to compress the spring 24. The extent to which the governor disc moves to the left is determined by the position of the friction pad 25 and consequently the speed at which the governor and the motor controlled thereby shall operate is determined and regulated by the position of the friction pad 25 with respect to the governor disc 17.

Referring now particularly to Figs. 1 and 2 wherein the parts are shown so adjusted as to cause the machine to operate as a variable speed machine, on the base plate 27 suitably secured to the motor-board 1 by screws 28 is pivotally mounted the variable speed controlling cam member 29, the same comprising an arm 30 preferably provided at its outer end with an antifriction roller 31 mounted on a pin or screw 32 fixed to said

arm, said roller being adapted to smoothly fit into a slot 33 in an arm or bracket 34 rigidly secured to the underside of the tone arm 12 as by screws or rivets 35, and having the free end thereof extending under the turntable 11 as clearly shown in Fig. 4.

Said member 29 also comprises a cam 36 and a rather long pivot pin 37 rigid therewith and preferably fitted into a socket 38, rigidly mounted in the base plate 27, and providing a smooth bearing for said pivot pin 37.

In the bottom of said socket 38 is preferably seated a ball 39 forming a thrust bearing for the pivot pin 37.

To prevent the accidental removal of the member 29 from the plate 27, said pivot pin is preferably provided with a groove 40 into which fits the free offset end 41 of the bracket 42 rigidly secured to the base plate 27 by a screw 43, said free end 41 being provided with a semicircular recess which fits closely around and adjacent the bottom of the groove 40 in the pivot pin 37.

The cam surface 36' of the cam 36 is preferably arranged so that it decreases or recedes toward the axis of the variable speed cam member 29 as the sound box moves toward the center of the turntable.

The cam surface 36' is arranged to cooperate with a friction pad controlling member 44 which preferably comprises a bell crank lever having one arm 45 provided at its free end with an antifriction roller 46 mounted to rotate smoothly on a pin or stud 47 on said lever and to normally bear against the cam surface 36'. The other arm 48 of the lever 44 is preferably provided with a straight edge 49 extending radially from the axis of the pivot pin 50 which is rigidly mounted in the lever 44. The pivot pin 50 is rather long and is smoothly journaled in a socket 51 (see Fig. 12) which in turn is rigidly mounted in and carried by the main conversion member 52. In the bottom of this cup or socket 51 is a thrust ball bearing 53 upon which the lower end of the pivot pin 50 rests. The accidental removal of the friction pad controlling member 44 from its bearing in the socket 51, is preferably prevented by a bracket 54 which may be rigidly secured to the member 26 by a screw 55, said bracket having a free offset end 54' adapted to extend over the upper surface of the bell crank lever 44 and to bear upon the upper end of the pivot pin 50.

The friction pad carrying member 26 (see Figs. 5 and 6) is a long irregularly shaped member and carries near one end thereof a downwardly extending bracket or arm 56 in the free end of which is mounted the friction pad 25. When mounted on the plate 27, this bracket or arm 56 extends downwardly through a suitable opening 27' 130

over the governor and into the path of the governor disc 17. On the upper side of said member 26 and near the end thereof is an antifriction roller 57 mounted to turn on a pin or stud 58, while the other end of said member 26 is provided with a relatively long rigid pivot pin 59 extending downwardly therefrom and fitting into a socket 60 (see Fig. 11) rigidly secured to the speed adjustment member 61. The lower end of this pivot pin 59 preferably rests on a ball thrust bearing 62 in the bottom of said cup or socket 60 and said pin smoothly fits into the bore of said socket 60. To prevent the accidental removal of the friction pad carrying member 26 from said socket 60, I preferably provide a bracket 63 secured to the speed adjustment member 61 by a screw 64, said bracket having an overhanging upper end 63' adapted to bear on the top of the pivot pin 59. On the underside of the member 26 I preferably provide a stud or projection 65 adapted to bear on and slide over the plane upper surface of the base plate 27 so that such friction pad carrying member may swing on its pivot pin 59 smoothly in a horizontal plane parallel to the upper surface of the base plate 27.

When the member 26 is mounted in the manner above referred to, the antifriction roller 57 at the outer end thereof is in the plane of the arm 48 of the friction pad controlling member 44 as the latter swings about its pivot pin 50 and the straight edge 49 of said arm 48 is normally in engagement with said roller 57.

About the pivot pin 59 of the friction pad carrying member 26 a spring 66 is preferably coiled, one end of said spring being hooked over the edge of the speed adjustment member 61 and the other end of said spring being hooked over the edge of said friction pad carrying member, the tension of said spring 66 being such as to tend to throw the friction pad carrying member 26 in an anticlockwise direction (Fig. 1) about the axis of its pivot pin 59 to normally hold the roller 58 against the straight edge 49 of the friction pad controlling member 44.

The speed adjustment member 61 comprises a two armed lever, to the end of one arm 67 of which the said friction pad carrying member 26 is pivotally connected, as above described, and to the other arm 68 of which is attached a handle 69. A pointer 70 adapted to be manually moved with the member 61 over a suitable dial 71 to different positions is at the end of the arm 68. This speed adjustment member 61 is pivotally mounted on a stud 72 (see Fig. 13) rigidly secured to and extending upwardly from the base plate 27, a friction washer 73 being preferably passed over the stud 72 before the speed adjusting member 61 is placed thereon so that the washer 73 is in-

terposed between the member 61 and the top of the plate 27. Another friction washer 74 is preferably placed on the stud 72 and above the member 61 so that the speed adjusting member is located between the two friction washers 73 and 74. The stud 72 is also preferably provided with a circumferential channel or groove 75 just above the upper friction washer 74 for the reception of a U-shaped buckled spring 76 which when slipped into the channel 75 applies a friction to the free movement of the member 61 and holds the said member 61 firmly in any adjusted position. The operation of this speed adjusting mechanism will be further described below.

The main motion conversion member 52 is pivotally mounted on the base plate 27 on a pivot pin 77, a washer 78 (see Fig. 10) being preferably interposed between the base plate 27 and the member 52 so that the arms of the lever or member 52 swing in a plane parallel to but just above the plane of the top surface of the base 27. The base plate 27 and motor-board 1 are both provided with aligned arc-shaped slots 79 so that the socket or cup 51 may project freely therethrough and swing about the axis of the lever 52 without contact with the base plate 27 or the motor-board 1 (see Fig. 12). This arc-shaped slot 79 is concentric with the axis of the pivot pin 77.

Projecting outwardly from the axis of the stud or pivot pin 77, the member 52 is provided with an arm 80, the outer end of which is provided with an offset shoulder 81 extending upwardly therefrom, and through this offset end or shoulder 81 is threaded an adjusting screw 82, preferably provided with a lock nut 83, and lying in the plane of the end of the arm 48.

The opposite end of the member 52 is provided with a pin or stud 84 to which one end of a link 85 is pivotally attached, the other end of said link being pivotally connected to the free end of one arm 86 of a bell crank lever 87 by a pivot pin 88. The other arm 89 of the bell crank lever 87 is provided with a handle 90 by means of which the bell crank lever 87 may be manually swung or moved on its pivot pin 91 fixedly mounted in the base plate 27. This member 52 with the link 85 and bell crank lever 87 constitute the main operative parts of what may be termed the conversion mechanism.

Also secured to the base plate 27 by a screw 92 is an arm 93 having an end 93' upturned into the path of the movement of the member 26 about its pivot 59 but below and out of the plane of the end of the arm 48 of the member 44. This arm 93 may be adjustably positioned so as to prevent any excessive movement of the member 26 into an anticlockwise direction about its pivot 59.

during the manipulation of the conversion movement. It may here be noted that when the conversion motion lever 87 is in the position shown in Fig. 1, then the mechanism 5 is set for variable speed operation and when the lever 87 is thrown to 180° the position shown in Fig. 3 then the mechanism is set to operate as a constant speed machine. By making that end 85' of the link 85 which is 10 attached to the conversion motion lever 87 curved so that it substantially fits around the hub of the lever 87, the contact of the concave edge of the curved part 85' of the link 85 with the said hub provides a limit 15 or stop-motion for the lever 87 in an anticlockwise direction and the contact of the convex edge of the said curved end 85' of said link 85 with the downwardly offset end 89' of the arm 89 forms a limit or stop- 20 motion for the member 87 in a clockwise direction. By swinging, then, the lever 87 to the limits of its motion in either direction, the talking machine above described 25 is most easily and readily converted from a constant speed machine into a variable speed machine and vice versa.

To provide for the free and unrestrained movement of the socket or cup 60 about the axis of the pivot pin 72 of the speed adjustment member 61, the base plate 27 is provided with an arc-shaped recess 94 and the motor-board is provided with a similar arc-shaped hole 94' in registration therewith as is clearly shown in Fig. 11. Stop pins 35 95, 95 may be rigidly attached to the base plate 27 to limit the movement of the arm 68 in either direction.

Having now described with considerable particularity the structural arrangements 40 and dispositions of the various parts of the mechanism, the operation thereof will now be readily understood.

Referring first to Figs. 1, 2 and 4, in 45 which the mechanism is set for variable speed operation, the turntable 11 is assumed to be turning in a clockwise direction driven from the motor, the spindle 6 of which is turning in a clockwise direction. The governor is rotating and the centrifugal force 50 of the flyballs or weights 22 has drawn the governor disc 17 up against the face of the friction pad 25. The turntable may be assumed to be turning comparatively slowly in this position, the stylus 15 being assumed 55 to be in the outermost convolutions 96 of the record groove at the point 98.

As the tone arm is swung transversely 60 over the face of the record by reason of the engagement of the stylus with the sound record groove, the arm or bracket 34 is swung with it from the position shown in full lines in Fig. 1, slowly into and through the first position shown to the left in Fig. 1 in dotted lines, and finally to the second 65 position shown to the left in dotted lines

wherein the stylus is in engagement with the innermost convolutions 99 of the sound record groove and at the point 100.

This slow motion of the arm or bracket 34 causes the variable speed control cam 70 member 29 to slowly swing about the pivotal axis of the pin or stud 37 in an anticlockwise direction from the position shown in full lines in Fig. 1 to that shown in Fig. 2. During this slow swinging movement of 75 the member 29, the roller 46 on one end of the arm 45 of the friction pad controlling member 44 follows downwardly on the cam surface 36' by reason of the pressure exerted by the spring 66 on the friction pad carrying member 26, the roller 57 on the end of which is held spring pressed against the straight edge 49 of the arm 48 of the member 44. Thus the roller 46 is held pressed against the cam surface 36' throughout the 80 traverse of the tone arm 12 over the record 85 16 during the reproduction of sound therefrom.

But as the friction pad controlling member 44 thus slowly swings in an anticlockwise direction about its pivot pin 50 permitting the friction pad carrying member 26 to thus slowly swing about its pivot pin 59 in an anticlockwise direction, the friction pad 25 is constantly slowly moved to 90 the left into the position shown in Fig. 2. The centrifugal force developed by the rotation of the governor shaft 9 draws and holds the face of the governor disc against the pad and the speed of the motor therefore 95 constantly increases throughout the travel of the tone arm over the record during the reproduction of sound therefrom.

Whether the rate in the increase in the speed of the motor be constant or variable 100 depends upon the shape of the cam 36'. The operation may be either, and if the record be originally recorded in a master tablet by a mechanism controlled by a similar cam, then the reproduction of sound from such 105 a record will be like the original sound recorded. My invention comprehends the operation of a variable speed machine wherein the rate in the change in the speed is constant or variable.

During this reproduction of sound at a 110 variable speed the only parts of the speed controlling mechanism which are actuated by the arm or bracket 34 are the variable speed controlling cam member 29, the friction pad controlling member 44 and the friction pad carrying member 26. All the other parts of the said mechanism shown in 115 Figs. 1 and 2 are unaffected by the movement of the tone arm.

If now it should happen either from the initial adjustment of the motor or from wear of the various parts, such as a wear 120 in the surface of the friction pad 25, that the speed of the turntable is not the proper 125 130

speed for the reproduction of a particular selection recorded in the record tablet, such for instance, as the pitch of the selection being too high or low as reproduced on the machine, the operator may throw the pointer 70 of the speed adjustment member 61 to the right to decrease the speed of the motor and to lower the pitch of the selection being reproduced, or to the left to increase the speed of the motor and raise the pitch of the selection being reproduced. When this speed adjusting member 61 is swung to the right, the end of the friction pad carrying member 26 connected thereto swings to the right, turning the pad carrying member 26 about the fulcrum bearing provided by the roller 57 on the straight edge 49 and at the same time drawing the said member 26 along the straight edge 49, which, as above described, preferably makes a slight angle to a plane normal to the axis of the governor shaft 9. This movement of the member 26, therefore, moves the friction pad 25 transversely to the face of the disc 17, and at the same time slightly against it, thus forcing the disc 17 to the right and reducing the speed of the governor and the mechanism controlled thereby. Conversely, a movement of the lever 68 to the left slightly moves the pad 25 to the left and increases the speed of the motor. A considerable motion of the arm 68 produces a relatively slight motion of the friction pad 25 toward or away from the friction pad 17 and thus is operated a delicate speed adjusting mechanism to increase or diminish the speed of the motor.

But this manual operation of the speed adjusting member 61 does not affect or move in any way the variable speed controlling mechanism or change the adjustment of the parts thereof with respect to each other. Thus, while the speed varying mechanism is operated to reproduce sound from a record tablet, the pitch may be varied without interrupting the continuous operation of the speed varying mechanism.

After the sound recorded in a sound record tablet has been reproduced, the sound box 50 may be lifted from the record and swung to the left outwardly to the periphery of the record and again placed in the sound record grooves for a second reproduction of sound from the record without stopping the motor. In thus swinging the tone arm outwardly to the periphery of the record, the variable speed controlling cam member 29 will be turned in a clockwise direction about its pivot pin 37 forcing the bell crank lever 44 in a clockwise direction about its pivot pin 50 and thus forcing the pad carrying member to turn in a clockwise direction about its pivot pin 59, thus forcing the friction pad 25 against the governor disc 17 and moving the governor disc 17

back to the position shown in Fig. 1, thus reducing the speed of the governor to that appropriate for the reproduction of sound from the outermost convolutions of the record. If for any reason the stylus be not swung outwardly to a position corresponding to that indicated by the numeral 98 but to some position intermediate the positions 98 and 100, as for instance, to reproduce a second time a certain part of the recorded selection, then it will be observed that the roller 46 of the member 44 will be on that part of the cam surface 36' which corresponds to the speed at which the record should rotate for that particular part of the record. In other words, to whatever position the stylus may be moved over the face of the record and then brought into engagement with the surface of the record, then the speed of the turntable will be the correct speed for the reproduction of sound from that particular part of the record tablet. After having once been set to operate as a variable speed machine, the machine may be operated like an ordinary talking machine by placing the stylus on any part of the record and correctly reproducing sound therefrom.

Referring now to Figs. 2 and 3, it may be assumed that after the reproduction of sound from a variable speed record has been completed and the parts are in the position shown in Fig. 2, the conversion motion member 89 has been swung from the position shown in Fig. 2 to the position shown in Fig. 3. In swinging the handle 90 from the "long" position to the "ordinary" position, the member 87 has been swung through substantially 180° and the link 85 has been thrown a distance substantially equal to the length of the throw of the crank or pivot pin 88 about the pivot 91 of the member 87. This longitudinal movement of the link 85 swings the motion conversion member 52 in a clockwise direction about its pivot pin 77 from the position shown in Fig. 2 to that shown in Fig. 3. This rotation of the member 52 about its pivot pin 77 carries the friction pad controlling member 44 downwardly and away from the cam 36 but the pressure of the roller 57 against the straight edge will hold the roller 46 against the cam surface 36' until the backside of the arm 48 encounters the free upturned end 93' of the rigid stop arm 93. After this engagement the arm 48 is no longer turned in an anti-clockwise direction by the free end of the pad carrying member 26 but the pivotal socket 51 in which the pad controlling member 44 is pivoted continues to move downwardly or in a clockwise direction about the pivot 77 carrying the arm 45 of the member 44 downwardly and away from the cam surface 36'. This motion conversion member 52 is thus turned about its pivot 77, the arm

80 is swung toward the arm 48 of the pad controlling member 44 and the end of the adjusting screw 82 finally engages the back-side of the arm 48. This screw 82 is so adjusted and set that when the handle 90 of the member 87 has reached the position shown in Fig. 3, the end of the screw 82 shall have engaged the arm 48 of the pad controlling member 44 and moved it about its pivot 50 and with it the friction pad carrying member about its pivot 59, a distance sufficient to bring the pad 25 into that position which will cause the turntable to revolve at the speed usually maintained in reproducing sound from constant speed records,—that is to say, into a position which will cause the turntable to revolve at substantially 78 revolutions per minute. The parts are now in the position shown in Fig. 3. The free end of the arm 45 of the pad controlling member is remote from the cam surface 36'. The tone arm may be swung about its pivot freely and in doing so it will swing the variable speed control cam member 29 about its pivot 37, but such motion is inoperative to produce any contact between the cam surface 36' and the roller 46. With the parts constructed, arranged and disposed in the manner above described, the tone arm is substantially just as free to be swung over the record as it would be in an ordinary constant speed machine.

In thus swinging the conversion motion lever from the position shown in Fig. 2 to that shown in Fig. 3, the variable speed mechanism is thrown completely out of action and the constant speed controlling mechanism, comprising the arm 80, the adjusting screw 82 and the lock nut 83, is thrown into operation to set the governor for constant speed reproduction.

But having been thus set for constant speed reproduction, it may be that by reason of faulty adjustment or wear of the parts that the turntable is running a little faster or a little slower than the standard speed of 78 revolutions per minute for the reproduction of sound from ordinary constant speed records and if for that or any reason it is desired to increase or diminish the speed of the motor it is merely necessary to adjust the lever 68 slightly to the right to decrease the speed, or slightly to the left to increase the speed of the motor. And this adjustment of the speed for constant speed operation is precisely like that for variable speed operation in that no parts of the mechanism are moved except the speed adjustment member 61 and the pad supporting or carrying member 26, the friction pad on the member 26 being moved over the face of the friction disc 17 and slightly against it when the lever 68 is moved toward the "slow" position and away from the face of

the governor disc 17 when the said lever 65 is moved toward the "fast" position.

It is to be noted that if the rigid stop arm 93 were to be omitted and the conversion lever 87 were to be swung from the position shown in Fig. 2 to that shown in Fig. 3, the pressure of the free end of the pad supporting member 26 would continue to swing the member 44 about its pivot and would hold the roller 46 against the cam surface 36' until the end of the screw 82 shall engage the back of the arm 48 of the lever 44. The distance which the friction pad might thus move away from the governor disc 17 before the engagement, above referred to, of the screw 83 with the back of the arm 48 might be considerable, and enough to permit the governor to rotate at an excessively high speed, possibly higher than that at which it was designed to run, with the result that the governor might become broken or strained to an extent sufficient to injure or interfere with its proper operation. The free end of the rigid arm 93 is therefore preferably adjusted so that the upturned end 93' thereof will be engaged by the pad carrying member 26 during the operation of the motion conversion member as soon as the pad reaches a position which permits the governor to revolve a little faster than it does when the machine is being operated at its highest speed as a variable speed machine. When, therefore, the motion conversion lever 87 is swung to the position shown in Fig. 3, the end of the screw 83 should engage the back edge of the arm 48 just prior to the completion of its full movement, to move the member 26 slightly and out of engagement with the upturned end 93' of the arm 93.

It will now be seen that I have provided a mechanism in which a talking machine motor, or broadly, a talking machine, may be converted at will from a variable speed machine into a constant speed machine by merely throwing the lever 87 from one position to another and a constant speed machine 105 may be similarly converted into a variable speed machine by a simple movement of the lever in a reverse direction. Whether the machine be operating as a constant or as a variable speed machine, the speed of the 110 motor may be increased or decreased by a speed adjusting lever, the operation of which does not disturb in any way the adjustment of the parts of either the constant or the variable speed mechanism.

A minimum amount of work is imposed upon the stylus when operating with my invention. During the reproduction, the cam moves from a high to a low position and the roller slides or rolls down on the cam surface 36'. Upon the spring 66 is imposed the work of moving the friction pad during the reproduction of sound from a

record. The cam merely controls the position to which the free end of the arm 45 of the member 44 may move. The roller 47 follows the cam surface and movement is imparted to the lever 44 by the spring 66. The pressure between the roller 46 and the cam surface 36' is slight during the reproduction of sound from a record and consequently the friction between the cam 36' and the roller 46 is correspondingly slight. By manually throwing the motion conversion lever 87, the speed varying mechanism may be thrown at will out of operation and the pad will be simultaneously positioned with respect to the governor disc for constant speed operation of the motor, and, conversely, by throwing the lever 87 in the opposite direction, the constant speed varying mechanism is thrown absolutely out of operation and the speed varying mechanism is thrown into operation, to convert the machine from a variable to a constant speed machine and vice versa.

Having thus described my invention, what I claim and desire to protect by Letters Patent of the United States is:

1. In a talking machine, the combination with a motor, a turntable and a reproducer, of a constant speed controlling mechanism, a variable speed controlling mechanism actuated by said reproducer, and a conversion member connected to both said mechanisms and manually operative to alternately throw said mechanisms into operative relation with said motor.

2. In a talking machine, the combination with a motor, a turntable and a reproducer, of a constant speed controlling mechanism, a variable speed controlling mechanism actuated by said reproducer, a conversion member connected to both said mechanisms and manually operative to alternately throw said mechanisms into operative relation with said motor, and manually operable means cooperating with said mechanisms to increase or decrease the speed of said motor without disturbing the adjustments of either of said mechanisms.

3. In a talking machine, the combination with a motor, a turntable and a reproducer, of a constant speed controlling mechanism, a variable speed controlling mechanism actuated by said reproducer, a conversion member connected to both said mechanisms and manually operative to alternately throw said mechanisms into operative relation with said motor, and means to limit the speed at which said motor may run during the movement of said conversion member.

4. In a talking machine, the combination with a motor, a turntable and a reproducer, of a constant speed controlling mechanism, a variable speed controlling mechanism actuated by said reproducer, a conversion member connected to both said mechanisms and

manually operative to alternately throw said mechanisms into operative relation with said motor, and means to prevent said motor from racing during the operation of said conversion member.

5. In a talking machine, the combination with a motor, a turntable and a reproducer, including a stylus to track in the groove of a disc sound record on said turntable, of a speed varying and controlling mechanism, and means to automatically progressively adjust said mechanism to accord with the position of the reproducer stylus with respect to a record on said turntable to produce a continually increasing angular speed of said turntable but a continually diminishing linear speed of the groove at the point of the engagement of the stylus therewith, as the reproducer moves toward the center of said turntable.

6. In a talking machine, the combination with a motor, a turntable and a reproducer, including a stylus to track in the groove of a disc sound record on said turntable, of a speed varying and controlling mechanism, and means to automatically progressively adjust said mechanism to accord with the position of the reproducer stylus with respect to a record on said turntable to produce a continually diminishing angular speed of rotation of said turntable but a continually increasing linear speed of the groove at the point of the engagement of the stylus therewith as the reproducer moves toward the periphery of said turntable.

7. In a talking machine, the combination of a motor, a turntable and a reproducer, including a stylus to track in the groove of a disc sound record on said turntable, of a speed varying and controlling mechanism, and means to automatically progressively adjust said mechanism to accord with the position of the reproducer stylus with respect to a record on said turntable to produce a continually increasing angular speed of rotation of said turntable but a continually diminishing linear speed of the groove at the point of the engagement of the stylus therewith, as said reproducer moves toward the center of said turntable and to produce a continually decreasing angular speed of rotation of said turntable but a continually increasing linear speed of the groove at the point of the engagement of the stylus therewith as said reproducer moves toward the periphery of said turntable.

8. In a talking machine, the combination with a motor, a turntable and a reproducer, including a stylus to track in the groove of a disc sound record on said turntable, of a speed varying and controlling mechanism, and means to progressively automatically adjust said mechanism to accord with the position of the reproducer stylus with respect to a record on said turntable to produce a con-

tinually increasing angular speed of rotation of said turntable as said reproducer moves toward the center of the turntable and to produce a needle speed of the peripheral convolutions of the record groove lower than that of the peripheral convolutions of a constant-angular-speed record of the same size, and higher than that of the peripheral convolutions of a constant-needle-speed record 10 of the same type.

9. In a talking machine, the combination with a motor, a turntable and a reproducer, including a stylus to track in the groove of a disc sound record on said turntable, of a speed varying and controlling mechanism and means to progressively automatically adjust said mechanism to accord with the position of the reproducer stylus with respect to a record on said turntable to produce a continually diminishing angular speed of the rotation of said turntable as said reproducer moves over said turntable toward the periphery thereof and to produce a needle speed of the peripheral convolutions of said record when said stylus is in engagement therewith lower than that of the peripheral convolutions of a constant-angular-speed record of the same size and higher than that of the peripheral convolutions of a constant-needle-speed record of the same size.

10. In a talking machine, the combination with a motor, a turntable and a reproducer, including a stylus to track in the groove of a disc sound record on said turntable, of a speed varying and controlling mechanism, and means to progressively automatically adjust said mechanism to accord with the position of the reproducer stylus with respect to a record on said turntable to produce a continually increasing angular speed of said turntable as said reproducer moves toward the center of said turntable and a continually diminishing angular speed of rotation of said turntable as said reproducer moves toward the periphery of said record and to produce a needle speed of the peripheral convolutions of said disc record when the stylus is in engagement therewith lower than that of the peripheral convolutions of a constant-angular-speed record of the same size, and higher than that of the peripheral convolutions of a constant-needle-speed record of the same size.

11. In a talking machine the combination with a turntable, a reproducer, a motor for rotating said turntable and a governor mechanism comprising a governor disc, a friction pad and centrifugal means for holding said governor disc against said pad to control the speed of said motor, of means to operate said motor at will as a variable speed or a constant speed motor, comprising automatic speed varying means for slowly moving said pad with respect to said gov-

ernor disc to increase the speed of said motor as the reproducer moves toward the center of said turntable and to decrease said speed as the reproducer moves toward the periphery of said turntable, and manually operable conversion means to throw at will said speed varying means out of operation and to simultaneously stationarily position said pad with respect to said governor disc for constant speed operation of said motor and conversely to throw at will said automatic speed varying means into operation and said pad from constant speed operation position. 70

12. In a talking machine, the combination with a turntable, a reproducer, a motor for rotating said turntable and a governor mechanism comprising a governor disc, a friction pad and centrifugal means for holding said governor disc against said pad to control the speed of said motor, of means to operate said motor at will as a variable speed or a constant speed motor, comprising automatic speed varying means for slowly moving said pad with respect to said governor disc to increase the speed of said motor as 80 said reproducer moves toward the center of said turntable and to decrease said speed as said reproducer moves toward the periphery of said turntable, manually operable conversion means to throw at will said speed varying means out of operation and to simultaneously stationarily position said pad with respect to said governor disc for constant speed operation of said motor and conversely to throw at will said speed varying means into operation from constant speed operation position, and manually operable speed adjusting means to adjust said pad toward and away from said governor disc without changing the adjustment of said 90 automatic speed varying means, or of said constant speed operation whether said motor is operating as a constant or a variable speed motor when said manually adjusting means are operated. 95

13. In a talking machine, the combination with a turntable, a motor for rotating said turntable and a governor mechanism comprising a governor disc, a friction pad and centrifugal means for holding said governor disc against said pad to control the speed of said motor, of variable speed controlling means for gradually automatically moving said friction pad with respect to said governor disc to operate said motor as a variable 100 speed motor, manually operable conversion means to throw at will said speed varying means out of operation and to simultaneously stationarily position said pad with respect to said governor disc to operate said 110 motor as a constant speed motor and manually operable speed adjusting means to adjust said pad with respect to said governor disc without affecting the adjustment of said automatic speed varying means or of 115 said constant speed operation. 120

65

said constant speed operation of said motor whether said motor is operating as a variable or as a constant speed motor.

14. In a machine for reproducing sound from a disc sound record tablet in which the record of sound is in the form of a spiral groove in a face thereof, the combination with a reproducer, a motor for rotating said tablet, a governor mechanism comprising a 10 governor disc rotated by said motor, a friction pad and centrifugal means for drawing and holding said governor disc against said pad during the rotation of said motor, of variable speed controlling means actuated by the reproducer to move said friction pad with respect to said governor disc to cause said motor to gradually increase in speed as the reproducer moves toward the center of said record tablet and to cause said motor to 15 gradually decrease in speed as the reproducer moves in the opposite direction, and means to throw at will said variable speed controlling means out of operation and to simultaneously adjust said pad into position 20 for constant speed record reproduction.

15. In a machine for reproducing sound from a disc sound record tablet in which the record of sound is in the form of a spiral groove in a face thereof, the combination 30 with a reproducer, a motor for rotating said tablet and a governor mechanism comprising a governor disc rotated by said motor, a friction pad and centrifugal means for drawing and holding said governor disc against said 35 pad during the rotation of said motor, of variable speed controlling means actuated by the reproducer to move said friction pad with respect to said governor disc to cause said motor to gradually increase in speed as the reproducer moves toward the center of 40 said record tablet and to cause said motor to gradually decrease in speed as the reproducer moves in the opposite direction, means to throw at will said variable speed controlling 45 means out of operation and to simultaneously bring said pad into position for constant speed record reproduction, and manually operable speed adjusting means to vary the position of said pad with respect 50 to said governor disc to increase or diminish the speed of the motor without changing the adjustment of said automatic speed varying mechanism or of said constant speed operation whether said motor is operating 55 at a constant speed or at a variable speed when said speed adjusting means are operated.

16. In a talking machine, the combination with a reproducer, a turntable, a motor for 60 rotating said turntable and a governor comprising a governor disc, a friction pad, and centrifugal means for holding said disc against said pad to control the speed of said motor, of mechanism to slowly move said 65 pad to gradually vary the speed of said mo-

tor for variable speed operation, a mechanism to accurately position and to hold stationary said pad for constant speed operation, a conversion member on which operative parts of said mechanisms are mounted, 70 and manually operated means for moving said conversion member to alternately throw said mechanism into operative relation with respect to said pad and governor disc to convert at will said machine from a constant 75 to a variable speed machine and from a variable to a constant speed machine.

17. In a talking machine, the combination with a reproducer, a turntable, a motor for rotating said turntable and a governor comprising a governor disc, a friction pad, and centrifugal means for holding said disc against said pad to control the speed of said motor, of mechanism to slowly move said pad to gradually vary the speed of said 80 motor for variable speed operation, a mechanism to accurately position and to hold stationary said pad for constant speed operation, a conversion member on which operative parts of said mechanism are mounted, 85 manually operated means for moving said conversion member to alternately throw said mechanisms into operative relation with respect to said pad and governor disc to convert said machine at will from a constant 90 to a variable speed machine and from a variable to a constant speed machine, and manual means operable independently of said mechanisms to move said pad with respect to said disc to vary and adjust the 95 speed of said motor.

18. In a talking machine, the combination with a motor, a governor therefor, a turntable driven by said motor and a reproducer, of a variable speed mechanism controlled 105 by said reproducer and acting on said governor to slowly vary the speed of said motor as said reproducer travels over a record on said turntable, and conversion means manually operable to render said variable speed mechanism inoperative and to simultaneously automatically set and hold said governor in a position at which said motor will revolve said turntable at a speed suitable for the reproduction of sound from constant 110 speed records.

19. In a talking machine, the combination with a motor, a governor therefor, a turntable driven by said motor and a reproducer, of a variable speed mechanism controlled by 120 said reproducer and acting on said governor to slowly vary the speed of said motor as said reproducer travels over a record on said turntable, and conversion means manually movable into one position to throw said variable speed mechanism into operative relation to said motor and into another position to render said variable speed mechanism inoperative and to simultaneously automatically set and hold said governor in 125 130

a position at which said motor will revolve said turntable at a speed suitable for the reproduction of sound from constant speed records.

5 20. In a talking machine, the combination with a motor, a turntable, a reproducer and a governor including a governor disc and a friction pad operating therewith, of a variable speed mechanism actuated by said 10 reproducer to slowly change the position of said pad as said reproducer moves over the turntable, and manually operable means for throwing at will said variable speed mechanism into and out of operative relation with 15 respect to said governor, and for simultaneously automatically moving said pad to, and holding it stationary in, a position at which said motor will revolve said turntable at the speed required for the reproduction 20 of sound from constant speed records when said variable speed mechanism is out of said operative relation.

21. In a talking machine, the combination with a motor, a turntable, a reproducer and 25 a governor including a governor disc and a friction pad operating therewith, of a variable speed mechanism actuated by said reproducer to slowly change the position of said pad as said reproducer moves over the 30 turntable, manually operable means for throwing at will said variable speed mechanism into and out of operative relation with respect to said governor, and for simulta-

neously automatically moving said pad to, and holding it stationary in, a position at 35 which said motor will revolve said turntable at the speed required for the reproduction of sound from constant speed records when said variable speed mechanism is out of said operative relation, and means independent 40 of said manually operable means to adjust the speed of said motor.

22. In a talking machine, the combination with a motor, a governor therefor, a turntable driven by said motor, and a reproducer, of a variable speed mechanism controlled by said reproducer and arranged to act on said governor to slowly vary the speed of said motor as said reproducer travels over a record on said turntable, and 45 conversion means manually movable into 50 two positions, in one of which said variable speed mechanism is rendered operative by said conversion means and in the other of which said variable speed mechanism is rendered inoperative and said governor is automatically set to and held by said conversion means in a position at which said motor will revolve said turntable at a speed suitable 55 for the reproduction of sound from constant 60 speed records.

In testimony whereof, I have hereunto set my hand this seventeenth day of October, 1924.

HORACE LEOPOLD TUCKER BUCKLE.
